UNITED STATES PATENT OFFICE.

JOSEF PETRZILKA, OF RACINE, WISCONSIN, ASSIGNOR, BY MESNE ASSIGNMENTS, TO THE NASH MOTORS COMPANY, OF KENOSHA, WISCONSIN, A CORPORATION OF MARY-LAND.

WIRE-SEAT STRUCTURE.

1,213,898.

Specification of Letters Patent. Patented Jan. 30, 1917.

Application filed July 19, 1915. Serial No. 40,631.

To all whom it may concern:

Be it known that I, JOSEF PETRZILKA, a citizen of the United States, residing at Racine, in the county of Racine and State of Wisconsin, have invented certain new and useful Improvements in Wire-Seat Structures, of which the following is a specification.

The ordinary form of wire seat structure comprises a wire base frame supporting a plurality of vertically positioned springs adapted to bear against the under portion of the seat. The seat portion is secured to an upper frame member and a leather or other suitable covering incloses the seat portion and has downwardly extending sides to complete the seat structure between the upper and lower frame members. Considerable difficulty has been experienced in properly securing the lower edge of the covering to the lower frame member.

My invention resides in the means for securing the lower edge of the covering to the lower frame member whereby a durable and rigid connection is made and the parts may be rapidly and economically assembled.

My preferred form of construction is shown in the accompanying drawing in which—

Figure 1 is a section on the line 2—2 of Fig. 2. Fig. 2 is a section of a portion of the seat structure showing a partial plan of the base.

Referring now more particularly to the drawing, my improved form of construction comprises a lower wire frame member 3, bent to the desired form to be given to the seat as a whole, and a similarly shaped upper frame member 4. Interposed between these two frame members 3 and 4 are a plurality of springs 5 which are held in proper relation to each other and to the frame members by suitable transverse and longitudinal tie-rods 6 and 7. The tie-rods extend between opposite sides of the base frame 3 and the ends of such rods are turned about the base frame 3 so as to form one or more convolutions and are provided with cover retaining portions 8 that extend beyond the base frame 3. Inasmuch as these tie-rods are generally spaced approximately 3 or 4 inches apart and extend between opposite sides of the seat frame, thus crossing each other at right angles, it will therefore be readily seen that about every three or four inches around the

base frame a tie-rod will be secured thereto and will have a projecting end 8 extending beyond the base frame.

The seat proper is preferably formed by an inner supporting fabric of canvas, burlap, or other coarsely woven material 9, against which the upper ends of the springs 5 bear, and an outer covering 10 preferably composed of leather or other suitable and durable material which is so cut as to leave a considerable space between it and the covering 9 to receive a suitable filling 11. It is customary to stitch or otherwise secure the outer covering 10 to the upper frame 4 but such stitching is not herein shown since it is customary in the art. The outer covering 10 extends downwardly from the upper frame 4 and terminates in a bead 12 along its marginal edge. Adjacent the bead 12 are a plurality of eyelets 13. These eyelets are so positioned along the bead so as to register with the extending ends 8 of the tie-rods 6. In assembling the structure, the upper and lower frames, together with the springs and tie-rods, are first assembled and the ends 8 of the tie-rods are left in a position at substantially right angles to the body of the rod. The lower covering 9, outer covering 10 and filling 11, are then suitably attached whereupon the lower edge of the covering 10 is brought into position whereby the projecting ends 8 of the tie-rods are passed through the eyelets 13 and are then bent inwardly and around the bead 12, thus firmly securing the lower edge of the covering 10 to the base frame 3.

It is of course obvious that instead of extending the ends of the tie-rod 6 so as to provide the necessary attaching means, a separate section of wire might be used and suitably connected to the base frame 3 whereby it would perform the same function as the extending ends 8 and, therefore, without limiting my invention to the precise details of construction herein shown.

I claim:

1. A wire seat structure comprising upper and lower wire marginal frames, a plurality of springs interposed between said frames, a covering for the seat structure extending downwardly between the upper and lower frames, wires extending between the sides of the lower frame and secured thereto by being coiled therearound, eyelets at the lower end of said covering in aline-

ment with said wires, the ends of said wires being normally straight to be received in said eyelets and then bent inwardly and upwardly to draw the lower edge of the 5 covering inwardly and toward the bottom of said seat structure.

2. A wire seat structure comprising upper and lower marginal wire frames, a plurality of springs interposed between said frames, 10 a covering for the seat structure extending downwardly between said upper and lower frames, a reinforcing wire secured in the lower end of said covering, wires extending between the sides of the lower frame and be-

ing secured thereto by being coiled there- 15 around, eyelets in said covering above its reinforcing wire and in line with said wires, the free ends of said wires being originally straight to receive the eyelets and being then bent inwardly and upwardly to loop around 20 the reinforcing wire of the covering and to draw it up against the base of the seat structure.

JOSEF PETRZILKA.
